ELECTRICAL CONNECTER PLUG

Charles E. Gilbert, New York, N. Y.

Application September 16, 1933, Serial No. 689,711

9 Claims. (Cl. 173—361)

This invention relates to devices for making electrical connection between an outlet for electrical current and an appliance or between two electric cords, and numerous other uses which will be evident to those skilled in the art.

Unlike the plugs which are in common use today this plug may be attached to the electric cord or other circuit without the removal of the insulation from the wires of the cord, and without the use of tools of any sort.

Furthermore, it consists of very few parts and is entirely free of screws or rivets or the like, may be manufactured by simple molding and stamping processes, and at very low cost. It is peculiarly adapted to machine assembly either with or without the cord since, as already stated nothing need be riveted, screwed or bolted. The parts are simply brought together and because of their inherent construction retain themselves in proper position and relation.

Although the form selected for illustration and description is an electric plug of generally conventional form since it is perhaps the simplest and easiest to describe, it will be understood that its external form is immaterial and that it need not even be a separate unit but may form an integral part of another electrical device such, for example, as a socket or vacuum cleaner.

A plug made in accordance with the invention is illustrated in the accompanying drawing, in which

Figure 1 is a side elevation of an assembled plug with an electric cord attached;

Fig. 2 is an end elevation of the plug of Fig. 1; Fig. 3 is another side elevation of the same plug rotated 90° from the position shown in Fig. 1 to illustrate the depressed finger grips by means of which it may be readily removed from the electrical outlet or appliance;

Fig. 4 is an end elevation of the body of the plug showing the recesses in which the contact blades are seated and other details, one recess containing a contact blade, the other being empty;

Fig. 5 is a cross-section of the plug along the line 5—5 of Fig. 2 showing one of the recesses with a contact blade in position therein and in contact with one of the insulated wires of an electric cord;

Fig. 6 is a cross-section of a plug along the line 6—6 of Fig. 4;

Fig. 7 is also a cross-section along the line 7—7 of Fig. 4 illustrating particularly the position assumed by the wires of the electric cord;

Fig. 8 is a fragmentary cross-section along the

line 8—8 of Fig. 4 to illustrate the preferred shape of the diagonal channel for the wires between the central opening of the plug and the recesses and Fig. 9 is an enlarged fragmentary diagrammatic view along the line 9—9 of Fig. 4.

As will be seen from the drawing the plug consists of but four parts,—a body 1 of substantially conventional external shape which may be molded from bakelite or suitable insulating material in a single piece and by a single molding operation, two contact blades 2, each of which may be stamped from a single piece of metal and also shaped by a single operation, and a disc 4 of insulating material which may also be formed by a single stamping operation and which closes the open end of the body.

The exterior of the body may be provided with depressed finger grips 5 to make it possible to remove it easily from the outlet or appliance. The body is provided with the usual longitudinal central aperture 6 through which the electric cord is inserted and also with two recesses 7 in which the contact blades are positioned. A channel 9 runs diagonally across the open face of the plug from substantially one corner of one recess to substantially the other corner of the other recess intersecting the central aperture. Through this channel the respective electric wires of the cord are led to the contact elements seated in the recesses. Preferably that part of the channel 10 between each recess and the central aperture 6 narrows from the upper edge towards the bottom as shown in Figs. 4 and 8, its dimensions in this portion being such that the electric wire lying therein will be wedged so that it will assume any strain placed upon the cord and will not permit such a strain to be conducted to the points of contact between the wire and the contact blades. The ends of channel 9, as shown at 11 in Fig. 4, are not so narrowed, extend to the bottom of recess 7 and the bottoms preferably curve upwardly and outwardly as best shown in Fig. 7 to accommodate the free end of each electric wire.

The open end of the body is depressed somewhat as best shown at 12 in Fig. 6 to provide a peripheral shoulder 13 around this end of the plug, this shoulder being formed so as to have a slightly undercut internal face 14.

The contact blade receiving recesses 7 are generally rectangular in shape, the inner wall being parallel to the central longitudinal axis of the plug, and the outer wall being generally parallel to the inner wall but provided with an inwardly projecting shoulder 16 at its lower end which

causes a constriction of the extreme lower part of the recess into which the end of the contact element will snugly fit. Near the upper edge of the outer wall on both sides of its mid-portion are inwardly projecting shoulders 17 which, as will be later described, engage with a part of the contact blade to retain the blade rigidly in position and prevent accidental displacement. Between shoulders 17 a depression 28 in the outer wall of recess 7 may be provided into which portion 24 of the contact blade may recede after the blade is inserted into the recess. At the end of each recess 7 where it is intersected by channel 9 shoulder 16 is terminated as shown in Fig. 4 leaving channel 9 free and clear with ample room for the insulated wire adjacent the point at which the blade makes contact with it.

The disc 4 which closes the body after the contact blades and wires have been assembled is shown at 4 in Figs. 2, 5 and 7. It is generally similar to the disc employed with plugs of common construction in that it fits the open end of the body and is provided with two apertures through which the contact blades pass. But unlike the ordinary disc instead of being retained simply by friction with the contact blades it snaps under under-cut edge 14 of the body and is thus firmly held in position, considerable effort being required to displace it. The shape of this disc which is shown with two curved cutaway portions is not material. It merely lends itself more perfectly to the body having the depressed finger grips. If these are omitted or if otherwise desired the disc may be of ordinary circular shape.

The contact blades 2 and 3 are best illustrated in Figs. 5, 6 and 9. Each may be formed from a flat piece of resilient conducting material by a single stamping and bending operation. Each consists of a prong 19, the form shown being that suitable for use with present day electrical outlets, a base portion 20 which seats in the recess of the body, an insulation piercing and contact making portion 21, and a portion 27 which engages with the shoulders 17 of the recess to lock the contact blade therein. Base portion 20 is simply an enlarged extension of prong 19 the width of which is such as to fit snugly but removably in the recess. At one lower corner, base portion 20 is cut away slightly and its lower edge provided with a series of teeth 22. The inner edge of this cutaway portion is also slit upwardly a short distance as shown at 23, which permits bending inwardly the edge which carries the teeth as best shown in Fig. 7. Toothed portion 22 when the contact blade is seated in the recess lies in the enlarged portion of the recess formed by the intersection therewith of diagonal channel 9, the teeth 22 lying close to but spaced slightly apart from the inner wall of the recess with teeth 22 facing the inner wall. Portion 24 of the contact blade is formed by longitudinally slitting the blade as shown at 25 and also slitting base 20 to form an arrow-shaped head 26. This tongue is bent as shown in Figs. 6 and 9 so that its point lies substantially in the plane of the base 20 but the upper edges 27 of the arrow head project outwardly from that plane. These edges 27 are so positioned that when the contact blade is inserted in the recess they will lie just below the lower edge of shoulders 17, the intermediate part passing between shoulders 17 into recess 28.

The plug is assembled as follows: A length of cord is passed through the central opening 6 and the outer woven insulation stripped from its end exposing the two wires within with their insulation

intact. These wires still with their insulation intact are laid along channel 9 one on either side of central opening 6. The contact blade is then pushed into its recess 7, the teeth 22 first bending the wire down into it. As soon as appreciable pressure has thus been placed upon the wire the part lying in the restricted portion 10 of channel 9 will become wedged and immovable therein. Consequently further downward motion of the contact blade into recess 7 will cause teeth 22 to scrape along the insulation of the wire until the contact blade is fully seated and to strip the insulation from the wire to that extent. This will also cause the teeth to scrape and enter between the strands of the wire itself to some extent making a clean and efficient contact therewith. This portion of the wire being jammed between the inner wall of the recess and the inwardly extending tooth portion of the contact, this action is positive and cannot fail to occur. During this operation the spear-headed tongue 26 has also entered the recess, this being made easy by the fact that its point lies in the same plane as the rest of the base 20, and outwardly projecting shoulders 27 have passed under shoulders 17 and now rest directly below and bearing against the shoulders. This effectively locks the contact blade into the recess. It cannot be removed unless shoulders 27 of the contact blade are sprung back out of contact with shoulders 17 of the recess. This cannot be done without the use of some sort of a tool. Therefore the contact blades are secure against accidental displacement. Disc 4 may then be slipped over prongs 2 and 3 and snapped into position under shoulder 13 closing the open end of the body. This disc is not essential since it is not intended to assist in the supporting or retaining of the contact blade and, since there is no exposed conductor, there is no possibility of short-circuiting as in the ordinary type of plug. Therefore, if desired, this disc may be eliminated. In that case the peripheral shoulder 13 may also be eliminated and that face of the body given a flat surface throughout.

Thus by simply bringing the cord into the plug, laying the wires across the recesses in the channel provided therefor, and inserting the contact blades in the recesses the entire plug is assembled, a perfect and enduring electrical contact is made with the conductors through the insulation thereof without exposing the conductors at any point where a short-circuit might occur and the entire assembly is maintained in this assembled condition without the aid of any screws, rivets, or other similar bolting means. At the same time the plug may be disassembled simply by disengaging the contact blades from the shoulders of the recesses and pulling them out. That part of the conductor at which electrical contact is made is protected from all external strain by the fact that the part lying in the constricted channel 10 is wedged tightly therein and will absorb it. The greater the strain the tighter this part of the conductor will be held. Thus the necessity of tying the two conductors together to obtain a knot larger than the central opening for the purpose of absorbing external strains is eliminated.

What I claim is:

1. An electrical connector which consists of a body provided with a longitudinal recess a wall of which has a shoulder adjacent its outer end, a contact blade seated in said recess and provided with means to pierce the insulation of an insulated wire and to make contact with the

- conductor within the insulation, and also provided with a resilient tongue having a shoulder which engages under the shoulder of said recess wall to lock the blade within the recess against retraction to maintain it positively in contacting position with the conductor.
2. An electrical connector comprising a body having a longitudinal recess a wall of which is provided with a shoulder adjacent its outer end and a central longitudinal aperture, a transverse channel intersecting said aperture and also said recess adjacent one end, a contact blade having a stepped edge seated in said recess, that portion of the stepped edge which registers with the intersecting channel having means for piercing the insulation of an insulated wire and making contact with the wire within, said contact blade also having means cooperating with said shoulder to lock said blade within said recess against retraction and to maintain it positively in contact with the wire.
3. An electrical connector comprising a body having a central longitudinal aperture and a longitudinal recess for the reception of an insulated wire and a contact blade, one side wall of which is substantially parallel to the longitudinal axis of the body, a contact element seated within said recess and having on one part of its lower edge means for jamming an insulated wire against said wall of said recess, said last mentioned means also being adapted to pierce and to strip the insulation from that part of an insulated wire which is jammed against said wall, said contact blade also being provided with means which cooperates with means in said recess to lock it within said recess against retraction and in wire contacting position.
4. An electrical connector comprising a body having a central longitudinal aperture and a longitudinal recess a wall of which is provided with a shoulder for the reception of an insulated wire and a contact blade, one side wall of which is substantially parallel to the longitudinal axis of the body, a contact blade seated within said recess and having on one part of its lower edge means for jamming an insulated wire against said wall of said recess, said last mentioned means also being adapted to pierce and to strip the insulation from that part of an insulated wire which is jammed against said wall, said contact blade also being provided with integral means for locking it within said recess in wire contacting position, said locking means consisting of a resilient tongue one end of which is offset to engage with the shoulder on the recess wall.
5. An electrical connector comprising a body having a longitudinal recess, a shoulder projecting into said recess adjacent its open end, a central longitudinal aperture separated from
- said recess by a wall, a transverse channel intersecting said central aperture wall and recess along which an insulated wire may be conducted from said central aperture into said recess, that portion of said channel which intersects said wall being narrower towards its bottom and shallower than the other portion, a contact blade seated in said recess and provided with means for jamming an insulated wire against said wall, and for stripping the insulation from that part of the insulated wire which is jammed against the wall, making contact with the conductor within, and means on said blade engaging under said shoulder in said recess to lock said blade within said recess.
6. An electric connector comprising a body provided with a longitudinal recess, a contact blade seated within said recess having an offset upwardly extending resilient tongue, a shoulder on a wall of said recess the under side of which engages with said tongue to lock said contact blade within said recess against retraction, and means on that part of said contact blade which is seated in the recess for piercing the insulation of an insulated wire and making contact with the wire within.
7. An electric connector comprising a body having a recess for the reception of an insulated wire, a contact blade one end of which is seated within said recess, said end terminating in means for piercing the insulation of an insulated wire and making contact with the wire within, an offset tongue on said blade, a shoulder in said recess engaging with said tongue to lock said blade within said recess against retraction in wire contacting position.
8. An electrical connector comprising a body provided with a longitudinal recess for the reception of a contact blade, a contact blade adapted to be seated in said recess and provided with means for piercing the insulation of an insulated wire and for making contact with the wire within when said blade is seated, a locking member on said blade which engages with the body when the contact blade is fully inserted into its recess to positively lock it against retraction and in wire contacting position.
9. An electrical connector comprising a body provided with a longitudinal recess for the reception of a contact blade, a contact blade adapted to be seated in said recess and provided with means for piercing the insulation of an insulated wire and for making contact with the wire within when said blade is seated, a locking member on said blade which engages with a wall of said recess when the contact blade is fully inserted into the recess to positively lock it against retraction and in wire contacting position.
